UTILITY SERVICE-TRUCK BODY

John J. Powers, Ladue, Mo., assignor to McCabe-Powers
Body Company, St. Louis, Mo., a corporation of Mis-
souri

Filed Sept. 14, 1959, Ser. No. 57,531

Term of patent 14 years

(Cl. D14—3)

FIG. 1

FIG. 2

FIG. 3

FIG. 4

Fig. 1 is a left side elevational view of a utility service-truck body embodying my new design;

Fig. 2 is a rear elevational view thereof;

Fig. 3 is a right side elevational view thereof; and
Fig. 4 is a top plan view thereof.

The fragmentary broken line showing of the truck is
for purposes of illustration only.

I claim:

The ornamental design for a utility service-truck body,
substantially as shown and described.
